UNITED STATES PATENT OFFICE

159,491

PIN OR SIMILAR ARTICLE

Walter Lampl, Jr., New York, N. Y.

Application October 21, 1949, Serial No. 5,613

Term of patent 3½ years

(Cl. D45—19)

To all whom it may concern:

Be it known that I, Walter Lampl, Jr., a citizen of the United States of America, residing at 608 Fifth Avenue, city of New York, county of New York, and State of New York, have invented a new, original, and ornamental Design for a Pin or Similar Article, of which the following is a specification, reference being had to the accompanying drawing, forming a part thereof:

Fig. 1 is a front elevational view of a pin embodying my new design;

Fig. 2 is a rear elevational view thereof with the pin fastener omitted;

Fig. 3 is a side elevational view of the pin; and

Fig. 4 is a view, partially in section, taken on the line 4—4 of Fig. 1.

The dominant feature of the design resides in the portions shown in full lines.

I claim:

The ornamental design for a pin or similar article, as shown and described.

WALTER LAMPL, JR.
